MEANS FOR PROVIDING SUCTION FOR OPERATING POWER ACTUATORS

Filed Nov. 25, 1925

UNITED STATES PATENT OFFICE.

CALEB S. BRAGG, OF PALM BEACH, FLORIDA, AND VICTOR W. KLIERSATH, OF PORT WASHINGTON, NEW YORK, ASSIGNEES TO BRAGG-KLIERSATH CORPORATION, OF LONG ISLAND CITY, NEW YORK, A CORPORATION OF NEW YORK.

MEANS FOR PROVIDING SUCTION FOR OPERATING POWER ACTUATORS.

Application filed November 25, 1925. Serial No. 71,270.

Our invention consists in the novel features hereinafter described, reference being had to the accompanying drawing, which illustrates one form in which we have contemplated embodying the invention and carrying it into effect, and the said invention is fully disclosed in the following description and claims.

Our invention relates to a new method of, and apparatus for, operating a power actuator or servo motor in which differential pressures are obtained by means of a partial vacuum operating on one face of the piston, and atmospheric air or other higher pressure fluid operating on the other face of the piston, suction for producing the desired rarefaction or partial vacuum being obtained from an internal combustion engine.

Our invention is particularly applicable to the operation of power actuators employed in connection with automotive vehicles operating on land, on or in water, or in the air, and especially for the operation of vacuum brake mechanism for automotive land vehicles. In the operation of such power actuators, it has been customary to obtain the necessary suction or rarefaction by means of a pipe connection to the suction passage of the internal combustion engine of the vehicle, between the throttle valve and the engine cylinders, and usually by tapping the intake manifold of the engine. As the operation of the internal combustion engine depends upon its receiving a proper supply of explosive mixture, composed of air and fuel, ordinarily liquid hydrocarbon fuel, in accurate proportions, usually determined by the careful adjustment of the carburetor needle valve, it necessarily follows that the withdrawal of any large quantities of atmospheric air from a power actuator and its discharge into the explosive mixture passing through the manifold to the several cylinders of a multi-cylinder engine, will of necessity reduce the degree of rarefaction in the manifold or other portion of the suction passage with which it is connected, and interfere with the operation of the engine, either by unduly diluting the explosive mixture with air, or by so reducing the degree of rarefaction in the manifold that proper quantities of fuel will not be drawn in from the carburetor. In either case, the operation

of the engine will be interfered with materially, and it is very likely to stall if idling, thereby destroying the source of suction upon which the operation of the actuator depends, it being understood that the rarefaction in the manifold increases as the throttle valve is closed.

The object of our invention is to utilize the suction produced by the suction stroke or strokes of the piston or pistons of the internal combustion engine for the operation of a power actuator, without connecting the power actuator with the intake manifold and without connecting it to any part of the suction passage between the carburetor or the throttle valve and the engine cylinders, so that none of the air exhausted from the power actuator will at any time be discharged into the intake manifold or any other portion of the suction passage, delivering charges of explosive material to the cylinder or cylinders, and to this end, we connect the power actuator to one or more, but less than all of the cylinders of a multi-cylinder engine, so that air exhausted from the power actuator will be delivered directly into an engine cylinder or cylinders less than all of the engine cylinders, so that even should the operation of such cylinder or cylinders, but less than all of the cylinders of the multi-cylinder engine, as are directly connected with the actuator be affected, the remaining cylinders of the engine will secure their normal charges under the control of the throttle valve, and the stalling of the motor while idling will be positively prevented.

In an internal combustion engine of the four cycle type, having four or more cylinders (which is the customary practice in the larger automotive vehicles), there is a continual state of rarefaction within the intake manifold whenever the throttle is closed, the rarefaction being greatest when the throttle is fully closed for idling (that is, when the motor is turning over slowly with the clutch or gears disengaged). The inlet valve of a cylinder of the engine opens when the piston is approximately at the top of the stroke preceding the suction stroke, to effect communication between the cylinder and the intake manifold, at which time, when the motor is idling, the burnt gases of the power

stroke should be reduced to approximately atmospheric pressure, but the partial vacuum in the intake manifold tends to withdraw part of the unexpelled burnt gases into the intake manifold, which gases, with the fresh hydro-carbon mixture, are immediately sucked back into the cylinder as soon as the piston has traveled downward on the suction stroke sufficiently far to create a greater state of rarefaction within the cylinder than exists in the intake manifold. We therefore propose to connect the suction pipe from the power actuator, with the cylinder at or just below the point where the vacuum in the cylinder equals or slightly exceeds that in the intake manifold when the motor is idling. By so doing, any air exhausted from the power actuator will be sucked into the cylinder by the vacuum created in that cylinder, but will not be sucked through the open inlet valve into the intake manifold by the vacuum created therein by all cylinders, as would be the case were this pipe connected to the explosion chamber of the cylinder. As the capacity of one, two, or less than all the cylinders of a motor, as for example a four-cylinder, a six-cylinder or an eight-cylinder motor, would be more than ample to operate any power actuator used for braking purposes, or other purposes about an automotive vehicle, the air exhausted into the cylinder or cylinders may cause that cylinder or those cylinders with which the actuator is connected, to miss fire once or even several times in succession, but the other cylinders whose charges of explosive mixture are not in any way diluted or affected, will continue to function normally, so that there will be no danger of the motor stalling while idling. It follows, therefore, that by our present invention the use of restricting means in the suction pipe leading from the power actuator to the engine, may be dispensed with, and the instantaneous and unretarded operation of the actuator, with full power and efficiency, is at all times insured.

Obviously, an automatic check valve must be inserted in the suction pipe adjacent to the engine cylinder in order to prevent the gases produced by the explosion of the charges from passing through the suction pipe into the power actuator. This valve, however, being located a considerable distance from the head of the engine cylinder, as for example a distance therefrom substantially equal to half the stroke of the piston, such valve or valves will not be exposed to the highest heat nor to the highest pressure resulting from the explosion of the explosive charges, but are only submitted to relatively low pressures and temperatures, and will, therefore, function without difficulty.

In the accompanying drawings, we have il-

lustrated one arrangement for carrying our invention into effect, in which

Fig. 1 represents a diagrammatic view of an installation in an automotive vehicle for use on land, of a power actuator operatively connected with the brake mechanism of the vehicle and having its suction pipe connected to two cylinders of a six-cylinder internal combustion engine, for example.

Fig. 2 is an enlarged sectional view representing a cylinder of the engine to which the suction pipe is connected and showing the check valve located therein.

Fig. 3 is a sectional view of one form of suction actuated device or power actuator, indicated in Fig. 1, which we may employ in connection with our invention.

In Fig. 1 of the drawing, which represents a schematic or diagrammatic representation of an installation in an automotive vehicle embodying our invention, 60 represents the internal combustion engine of the four-cycle type, for propelling the vehicle which, in this instance, is shown, for example, as having six cylinders. 61 represents the intake manifold for supplying explosive charges to all of the cylinders and receiving the explosive mixture from the carburetor, 63, through a passage controlled by the usual throttle valve, 64. 70 represents diagrammatically the brake mechanism of the vehicle which may be of any particular type, and while only one brake mechanism is actually shown in Fig. 1, it is to be understood that any desired number of the wheels of the vehicle may be provided with brake mechanism simultaneously actuated. In this instance, the brake mechanism shown is provided with an operating lever, 72.

1, represents the cylinder of a power actuator, provided with a piston, 3, adapted to be moved in a direction to apply the brakes by atmospheric air (or other higher pressure fluid) acting on the rear face of the piston, a partial vacuum being produced in the cylinder forward of the piston, as herein-after described, suitable controlling valve mechanism being provided for controlling the actuator. The piston, 3, is provided with the piston rod 5, connected by a link, 73, with the operating lever, 72, of the brake mechanism (or mechanisms). In this instance, the valve mechanism shown, which is indicated at 40, 41 is located within the hub of the piston, and is of the construction shown and described and claimed in our former Patent No. 1,583,117, granted May 4, 1926, but it is to be understood that the particular form of actuator and the particular form of valve mechanism for controlling the same, form no part of our present invention and will not be specifically described or claimed herein.

In this instance, the cylinder on the forward side of the piston is directly connected

with the suction pipe, 52, and the valve mechanism is provided with means for admitting higher pressure fluid, as atmospheric air, to the cylinder on the other side of the 5 piston, through an air inlet aperture, 10, in the hollow piston rod, 5. The valve mechanism is operated in this instance by means of a hollow valve sleeve, 20, operatively connected with an operator operated part, as 10 a foot lever, 88, provided with the usual retracting spring, 89, by means of a link, 85. A forward movement of the foot lever operating the valve mechanism will bring about a forward movement of the piston 15 to apply the brakes; and vice versa, the return movement of the foot lever will bring about the return movement of the piston and release the brake mechanism.

The suction pipe, 62, is shown in this instance as connected to two of the cylinders only, 60^a and 60^b, of the engine, and as indicated in Fig. 2, the connection of the pipe, 62, to the cylinder, is at a point approximately midway of the stroke of the piston, 25 so that when the piston is at the top of its stroke, the communicating pipe, 62, will be closed by the piston. The suction pipe, 62, is also provided adjacent to each cylinder with which it is connected, with a check 30 valve, 66, normally held in seated position, in this instance by a spring, 67, so that when the cylinder port, indicated at 62^a, communicating with the suction pipe, 62, is uncovered by the piston during the power stroke following the ignition of an explosive charge, 35 the burnt gases of combustion will not be forced through the suction pipe, 62, into the actuator. 68, in Fig. 2, represents more or less diagrammatically the inlet valve for 40 controlling the admission of explosive mixture from the intake manifold, 61, into the cylinder, and each cylinder will of course be provided with the usual exhaust port and exhaust valve (not shown), as is customary 45 in internal combustion engines. When the engine is operating idly, with the throttle closed, or partly closed, there will be a certain amount of rarefaction in the manifold, 61, so that as the engine piston indicated at 50 59, rises on the exhaust stroke to expel the burnt gases previous to commencing the suction stroke and passes its highest position, the inlet valve, 68, will open and as a partial vacuum exists in the manifold, some 55 of the burnt gases will be drawn into the manifold, but as the piston descends on its suction stroke, these burnt gases will be drawn back into the cylinder together with a fresh charge of explosive mixture, as soon 60 as the downward movement of the piston effects rarefaction within the cylinder greater than that which exists in the manifold. Until that point is reached, the suction pipe, 62, is entirely cut off from the 65 cylinder by the piston itself, so that by no

possibility can any air be withdrawn from the actuator into the intake manifold, and therefore the explosive charges will be furnished to the other cylinders of the engine with which the suction pipe, 62, is not connected, without any dilution or other interference from the power actuator. When the piston has descended to or slightly beyond the point where the suction within the cylinder, 60^a, for example (as shown in Fig. 75 2) is greater than that in the manifold, the communicating aperture, 62^a, which communicates with the suction pipe, 62, will be uncovered by the piston and air will be withdrawn from the suction pipe, 62, and 80 from the actuator cylinder, if there is any air therein, at the same time that a partial charge of explosive mixture is drawn into the cylinder from the intake manifold. The valve, 66, in the suction pipe, 62, opens to 85 permit the withdrawal of air through the suction pipe, 62, into the cylinder, during the suction stroke, whenever there is sufficient air at higher pressure to overcome the light spring, 67.

In practice, we prefer to so arrange the controlling valve mechanism that the portion of the actuator cylinder forward of the piston is maintained in a rarified condition 90 of partial vacuum, and we may also so construct the valve mechanism as to maintain an equal state of partial vacuum on both faces of the piston, as set forth in our former application above referred to, in order that on the admission of atmospheric air or 95 other higher pressure fluid in rear of the piston, an instantaneous operation of the brake mechanism may be effected. The combination of this form of actuator as herein shown with a suction pipe leading to one, 100 or a small minority of the cylinders in the manner described, enables us to obtain additional advantages. The suction produced by one or this small number of cylinders is 105 of course greatly less than that which could be obtained by connecting the suction pipe with the manifold which would be subject to the suction from all the cylinders when the throttle is closed, and therefore where the forward end of the actuator cylinder is 110 not maintained in a state of rarefaction it will require a certain amount of time for the single cylinder, or few cylinders connected with the actuator, to exhaust the air 115 from the actuator and apply the brakes, and this might delay the application of the brakes in some cases. Where, as herein shown, the forward end of the cylinder (and in some instances both ends of the cylinder) are maintained in a state of rarefaction, the 120 air is exhausted between operations of the actuator when it is not in operation, and when the actuator is operated, it is only necessary to admit air in rear of the piston to 125 secure an instantaneous response of the ac- 130

tuator, and as no appreciable amount of air would be admitted to the cylinder, or cylinders of the engine, connected with the actuator during an application of the brakes, the engine is further protected against the possibility of stalling, if idling, and destroying the source of suction upon which the operation of the actuator depends. But this is not essential and if the controlling valve mechanism is operating at any time and under any condition so as to connect the suction pipe, 62, with the cylinder forward of the piston and admit atmospheric air or other higher pressure fluid in rear of the piston, the suction of the cylinders, as 60^a and 60^b, less than the whole number of cylinders in the engine, with which the suction pipe, 62, is connected, will be sufficient to exhaust the air from the cylinder forward of the piston and permit the atmospheric air or higher pressure fluid to move the piston forward in a direction to apply the brakes, and it will be understood that when the valve mechanism is reversed, the suction of the cylinder connected with the pipe, 62, will exhaust from the actuator cylinder the air admitted to effect the power stroke of the actuator piston and insure the release of the brake mechanism, either by permitting it to release itself (or by admitting atmospheric air or higher pressure fluid to the cylinder forward of the piston, to positively return the parts to their normal position).

In any case, any air admitted to the actuator cylinder for the purpose of actuating the piston therein, will be withdrawn through the suction pipe, 62, into the cylinders of the engine connected therewith, under the control of the reversing valve mechanism. This may temporarily dilute the explosive charges received by these cylinders to such an extent as to cause them to miss fire, but the remaining cylinders of the engine will receive their explosive charges without dilution under the control of the throttle valve, and will insure the continuous operation of the engine without danger of stalling if idling, and without any interruption of the suction upon which the operation of the actuator depends. It will be understood that should the cylinder or cylinders with which the actuator suction pipe is connected miss fire, by reason of the dilution of its charge by the air drawn in from the actuator, this will only occur occasionally and for a limited number of strokes of the pistons in such cylinders, and will not materially affect the running of the engine, while the necessary suction to effect the instantaneous operation of the actuator and the brake mechanism (or other device) connected therewith, with the full power of the actuator, will be assured at all times when the actuator is called into operation by the operation of its controlling valve mechanism. We

do not desire to be limited to exact location of the aperture in the cylinder with which the suction pipe leading to the vacuum or suction actuator is connected. We prefer to locate it at such a distance below the position occupied by the head of the piston, when in its highest position, that when said aperture is opened by the downward movement of the piston on the suction stroke, the degree of rarefaction within the cylinder shall be at least as great or greater than the degree of rarefaction existing in the manifold, with the object that no air drawn through the suction pipe at any time shall be permitted to pass into the intake manifold and affect the normal charges of combustible mixture passing to the other cylinders of the engine not connected with the suction pipe.

It will be noted that the suction pipe connects the actuator directly with a cylinder, or cylinders of the engine independently of the means for supplying the normal explosive charges thereto, delivering the air withdrawn from the actuator into the portion of the cylinder subject to variations of pressure by the movements of the piston, and the word "directly" in the following claims is used with that meaning. It will also be noted that by locating the port, 62^a, in the side of the engine cylinder in the position shown, it is closed by the piston during the first portion of the explosion stroke of the piston, thereby protecting the port from being closed by carbon.

What we claim and desire to secure by Letters Patent is:

1. The combination with an internal combustion engine of the four cycle type, provided with a suction passage for supplying explosive charges to the engine, of a suction actuated device comprising a cylinder, a piston therein, and controlling valve mechanism, and a suction pipe extending from the cylinder of the suction actuated device and connected to a cylinder of the engine adjacent to the position of the piston head therein, when said piston has moved far enough on its suction stroke to produce rarefaction within the cylinder greater than that existing in the charge supplying suction passage.

2. The combination with an internal combustion engine of the four cycle type, provided with a suction passage for supplying explosive charges to the engine, of a suction actuated device comprising a cylinder, a piston therein, and controlling valve mechanism, and a suction pipe extending from the cylinder of the suction actuated device and connected to a cylinder of the engine adjacent to the position of the piston head therein, when said piston has moved far enough on its suction stroke to produce rarefaction within the cylinder greater than that existing in the charge supplying suction passage, and a check valve interposed between the

cylinder and said suction pipe for preventing gases of explosion from passing to the actuator cylinder.

3. The combination with a multi-cylinder internal combustion engine of the four cycle type, provided with a suction passage for supplying explosive charges to all of said cylinders, of a suction actuated device comprising a cylinder, a piston therein, and controlling valve mechanism, means for connecting the cylinder of said suction actuated device with certain cylinders of the engine less than the whole number, at points adjacent to the position of the piston head therein, when the piston has moved far enough on its suction stroke to effect a rarefaction within the cylinder greater than that in the charge supplying suction passage, and a check valve for each cylinder, so connected with the suction actuated cylinder as to prevent the passage of gases of explosion to the cylinder of said suction actuated device.

4. In an automotive vehicle, the combination with a multi-cylinder internal combustion engine of the four cycle type, for propelling the vehicle, brake mechanism for the vehicle, of a suction actuated power actuator comprising a cylinder, a piston therein, operatively connected with the brake mechanism, and controlling valve mechanism, and a suction pipe for the actuator cylinder connected with certain cylinders of the engine less than the whole number, at a point with respect to each, adjacent to the position of the head of the piston therein, when the piston has moved on its suction stroke far enough to effect a rarefaction within the cylinder greater than that in the charge supplying suction passage.

5. The combination with an internal combustion engine of the four cycle type, provided with a suction passage for supplying explosive charges to the engine, of a suction actuated device comprising a cylinder and a piston therein, and controlling valve mechanism for the suction actuated device, and a suction pipe extending from the cylinder of the suction actuated device, under the control of the said valve mechanism, to a cylinder of the engine and connected to said cylinder by a port located in the side of the cylinder and adapted to be closed by the engine piston therein during the explosion stroke, until said piston has completed more than half of the travel of the explosion stroke

whereby the said port will be protected from being closed by carbon, and a check valve interposed between said cylinder ports and the suction pipe.

6. The combination with an internal combustion engine of the four cycle type, of a suction actuated device comprising a cylinder, a piston therein, and controlling valve mechanism, and a suction pipe extending from the suction actuated device and directly connected to a cylinder of the engine.

7. The combination with a multi-cylinder internal combustion engine of the four cycle type provided with means for supplying the normal explosive charges to said cylinders, of a suction actuated device comprising a cylinder and piston and controlling valve mechanism, and a suction pipe extending from the suction actuated device and connected directly to certain of the engine cylinders less than the whole number, whereby the withdrawal of air in the operation of the suction actuated device will not affect the explosive charges delivered to the other cylinders of the engine.

8. The combination with a multi-cylinder internal combustion engine of the four cycle type provided with means for supplying the normal explosive charges to said cylinders, of a suction actuated device and means for delivering air from said suction actuated device directly to the working chamber of a cylinder of said engine independently of the valve mechanism of the engine which normally controls the supply of explosive charges to the cylinders, said means operating on the suction stroke of the piston in said cylinder.

9. The combination with a multi-cylinder internal combustion engine of the four cycle type, of a suction actuated device, means for delivering air from said suction actuated device directly to the working chamber of a cylinder of the engine independently of the valve mechanism of the engine which normally controls the supply of explosive charges to the cylinders, said means operating upon the suction stroke of the piston in said cylinder and means for preventing the delivery of gaseous material from said cylinder to the suction actuated device.

In testimony whereof we affix our signatures.

CALEB S. BRAGG.
VICTOR W. KLIESRATH.
